CONDENSER CONTROL APPARATUS

Application filed January 3, 1929. Serial No. 330,121.

The invention relates to a method and apparatus for effecting the production by a continuously operating condenser of a blended condensate having a uniform composition.

5 An object of the invention is to provide a method by which the production of a condensate having a fixed and unvarying vapor pressure is assured.

Another object of the invention is to provide apparatus of the character described in 10 which the vapor pressure of the product automatically controls the operation of the condenser for providing a uniform product of predetermined volatility.

15 A further object of the invention is to provide a device of the character described which is particularly applicable in the production of hydro-carbon condensates.

Yet another object of the invention is to 20 provide a device of the character described which is readily applied in the control of the product of the various types of condensers apparatus now in use.

The invention possesses other objects and 25 features of advantage, some of which, with the foregoing, will be set forth in the following description of a preferred form of the invention and in the accompanying drawings in which,

30 Figure 1 is a generally diagrammatic elevation showing the device of the invention applied to one type of condensation apparatus, a condenser and accumulator of the apparatus being shown in section.

35 Figure 2 is an enlarged sectional elevation through a constant flow valve of the apparatus.

Figure 3 is an enlarged vertical section 40 through an evaporation cup of the device and an associated thermostatic means for effecting a control of the flow of a cooling fluid through the condenser.

Figure 4 is a sectional view of a modification 45 of the structure shown in Figure 3.

As particularly illustrated, the device of 50 my invention is disclosed in operative association with a condensing unit arranged for continuous operation and in which a mixture of water and hydrocarbon vapors is arranged 55 to be cooled for producing a blended hydro-

carbon liquid. For convenience, gasoline for use in internal combustion engines will hereinafter be presumed as the desired product, and the following description will be directed accordingly. The unit described, it 55 will be noted, would usually be one of a number of like units connected in series and differing essentially only in the condensation conditions therein, and a required number of 60 the units would be provided with the device of my invention for the independent control of said condensation conditions.

More specifically, the invention is disclosed 65 as it would be applied to a condenser 6 providing a vapor receiving cavity 7 which discharges into the cavity 8 of an accumulator 9, the latter being provided with discharge pipes 11, 12 and 13 for the condensed water, 70 condensed gasoline and uncondensed vapors, respectively. A suitable gas trap 14 is provided in the water pipe 11, while a suitable automatic back-pressure valve 15 is preferably provided in the vapor pipe 13 for maintaining the constancy of the vapor pressure 75 in the condenser and accumulator. Preferably, and as shown, the gasoline discharge pipe 12 is provided with a float controlled valve 16 for maintaining the constancy of the level of the gasoline above the outlet 80 therefor whereby the gasoline discharge pressure will be held constant. A cooling fluid such as water is arranged to be circulated under pressure through a worm 17 disposed in the condenser cavity 7 and having inlet and outlet pipes 18 and 19 therefor, one 85 of said pipes being provided with a valve 21 for regulating the flow rate of the cooling fluid through the worm.

It will now be noted that it has heretofore 90 been customary to control the composition of the gasoline produced in a unit such as that now described by maintaining a constant temperature condition in the condenser cavity, regulation of such temperature being made in accordance with the temperature at some fixed point of the condenser or the temperature of the discharged liquid. Preferably, the aforesaid regulation would be effected through the valve 21, it being noted 95 that the effective condensing temperature is 100

raised when the valve is closed to lessen the quantity flow of cooling fluid through the worm and is lowered when the valve is opened. Such regulation in terms of temperature presupposes, however, that the various vapor fractions are present in the delivered vapor in unvarying proportions, which condition is seldom, if ever true, so that the resulting gasoline will vary somewhat in the proportions of the different gasoline fractions therein and will be neither constant as to composition nor to essential qualities thereof.

In many products which must be obtained by fractional distillation, one quality which is frequently an important feature in their use is that of volatility. Thus in gasoline and other liquids which are to be used in carburetted form as fuels, the question of volatility is vital and the production of such a liquid to have an unvarying and fixed volatility becomes of primary importance. Under these circumstances, the usual control in terms of temperature is markedly ineffective. With the present invention, however, a product of constant volatility is obtained by controlling the composition thereof in terms of the volatility of the product as it is produced, and a preferred apparatus for this purpose will now be described.

As particularly illustrated in Figures 1 to 3 inclusive, an evaporation cup 22 is provided into the cavity of which a sampling pipe 23 connecting with the gasoline discharge pipe 12 is arranged to discharge. Preferably, the sampling pipe is connected to the pipe 12 at a point thereof between the float controlled valve 16 and the accumulator, whereby the effective pressure head at the intake thereof will be substantially constant. A suitable drier or dewatering trap 24 is desirably provided in the pipe 12 for reducing the water content of the sample to a minimum. Preferably, the liquid level in the cup 22 is arranged to be constant, and an overflow pipe 25 is provided for said cup whereby the gasoline sample may flow through the cup at a constant flow rate. To prevent the escape of vapors through the overflow pipe 25, the latter is preferably provided with a gas trap 26.

It will now be noted that evaporation is arranged to take place from the surface of the gasoline sample in the cup and that the rate of evaporation or volatility thereof is determined by the combined vapor pressures of the fractions in the sample, with the more volatile fraction a major factor in determining said evaporation rate. The heat of vaporization taken up by the resulting vapors will cool the liquid in the cup below the temperature at which it is supplied to the cup, the degree of cooling being determined by the degree of volatility of the gasoline, the quantity of liquid in the cup, and the rate at which the gasoline is supplied to the

cup, the last two factors being constant. The flow rate of the gasoline sample into the cup is preferably a constant minimum which will insure an overflow therefrom, and an automatic flow control valve mechanism 27 is preferably interposed in the sampling pipe 23 for providing the desired constant flow rate. The mechanism 27 particularly disclosed is hereinafter described in detail, Figure 2 disclosing an enlarged section therethrough.

Preferably, and as shown, the cup 22 is disposed in a heat insulating jacket 28 whereby the contents thereof may not obtain heat from the surroundings of the cup. Furthermore, the sampling pipe 23 is provided with a covering 29 of suitable heat insulation, as indicated in dash lines in Figure 1 and in full in Figures 2, 3 and 4. In this manner, any appreciable cooling of the sample by radiation is prevented and the lowering of the temperature of the liquid in the cup will be determined by and vary with the volatility of said liquid. The pipe 23 is preferably made as short as possible for further reducing heat losses.

It will now be noted that the valve 21 is arranged to be automatically controlled by the temperature obtaining in the evaporation cup 22. As shown, the bulb of a suitable expansion thermometer 31 is disposed in the liquid in the cup and said thermometer is operatively connected to an air valve 32 having an inlet pipe 33 for connection with a suitable source of air under pressure. The outlet pipe 34 of the air valve is connected with the valve 21, which valve, it will now be noted, is a power valve of the diaphragm type and is so connected with the pipe 34 that the passage provided therethrough for the cooling fluid will vary inversely with the pressure in the conduit. In this manner, a lowering in temperature of the liquid in the cup 22 from its desired constant value, indicating an increased volatility of said liquid, is arranged to decrease the quantity flow rate of the cooling fluid through the worm and so raise the effective condensing temperature for reducing the condensation of the more volatile fractions of the vapor mixture, thereby reducing the volatility of the gasoline subsequently produced. Correspondingly, a raise of the temperature of the liquid in the cup 22 is arranged to effect an increase in the quantity flow rate of the cooling fluid through the worm and so increase the volatility of the product. The air and water valves 32 and 21 respectively, it will now be noted, are initially cooperatively set for the maintenance of a predetermined temperature of the liquid in the cup 22, such temperature being determined in accordance with the desired volatility of the gasoline.

Means are preferably provided for insuring the maintenance of constant evaporation

conditions in the cup 22. As particularly disclosed in the embodiment of Figures 1 to 3 inclusive, such means comprises the use of a tight cover 35 for the cup and creating a constant and very slight suction in the cup space by connecting the same with a suction pipe 36. Preferably, and as shown, an automatic pressure control valve 37 is interposed in the pipe 36 for insuring the required minimum suction in the cup. In this manner, the constancy of evaporation conditions in the cup is arranged to be automatically maintained.

Preferably, the bulb of a second thermometer 38 is disposed in the liquid of the cup 22, said thermometer being operatively connected with an automatic recording device 39 having a record chart 41 preferably calibrated in terms of volatility. In this manner, any necessary adjustment of the control means for the motor valve 21 to provide a product of required volatility may be made while the apparatus is in operation. The thermometers 31 and 38 preferably extend through and are mounted on the cover 35, as shown.

Referring now more particularly to the structure of the constant flow mechanism 27 associated with the sampling pipe 23, which is disclosed in detail in Figure 2, it will be noted that said mechanism essentially comprises an orifice plate 40 and a diaphragm valve 42 both interposed in said pipe, the latter being closer to the cup 22. The valve 42 provides pressure chambers 43 and 44 at opposite sides of a diaphragm 45 thereof, said chambers being connected with the pipe 23 at opposite sides of the plate 40 by means of pipes 46 and 47 respectively. A bipartite rod 48 of adjustable length extends from the diaphragm 45, said rod carrying a valve disc 49 for various disposition with relation to the flow orifice 51 of the valve proper. The disc 49 is arranged to be disposed in accordance with the pressure differential at the opposite sides of the plate 40, adjustment for the desired minimum normal flow therethrough being effected by adjusting the length of the rod 48, as by means of the turnbuckle 52 shown. A spring 53 is provided for maintaining the contact of the valve rod with the diaphragm.

As particularly disclosed, the motor valve 21 and suction control valve 37 are constructed generally as is the valve 42 except that but one pressure chamber is provided, these chambers being respectively connected with the pressure and suction pipes 34 and 36. It is to be noted, however, that valves of other types and structure might be used in lieu of these valves for accomplishing the various purposes thereof without departing from the spirit of the invention.

In Figure 4, an alternative form of the evaporation cup is disclosed. In this em-

bodiment, a cup 54 of the hollow-walled vacuum bottle type is provided, said cup being open at the top. A stack 55 having vent openings 56 at the top thereof is disposed over the cup as a cover therefor whereby escape of the vapors is arranged to take place by reason of their vapor pressure. This method of controlling the evaporation conditions in the cup is not generally as positive as is the vacuum method previously described, but will be found satisfactory in many installations, and would, of course, be used where no suction pipe is available.

It will now be clear that the self regulating apparatus described, through the automatic maintenance of constant pressure conditions therein, is arranged to provide a product of constant and adjustably variable volatility. And it will be further noted that the device of my invention is applicable to many types of distillation apparatus for producing condensates of predetermined composition, reference being had to crude oil refining apparatus including topping plants, cracking plants, and pressure distillate stabilizing plants. Furthermore, the device may be used in the production of alcohols and other volatile liquids with equal facility.

From the foregoing description taken in connection with the accompanying drawings, the advantages of the construction and method of operation will be readily understood by those skilled in the art to which the invention appertains, and while I have described the principal of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In apparatus for producing a mixed condensate from hydrocarbon vapors, means providing a condenser chamber, means providing a stream of a cooling medium flowing through said chamber, means automatically operable to maintain a constant pressure in the chamber, and means automatically operable in accordance with the volatility of the condensate to so control the flow rate of said stream as to effect the production of a condensate of a constant and predetermined volatility.

2. In apparatus for producing a mixed condensate from hydrocarbon vapors, means providing a condenser chamber, a pipe extending through said chamber and carrying a stream of a cooling medium, a valve for controlling the flow rate of said stream, an evaporation cup, means supplying a continuous sample of the condensate to said cup, and

means automatically operated in accordance with the temperature of the liquid in said cup for controlling the setting of said valve.

3. In apparatus for producing a mixed condensate from hydrocarbon vapors, means providing a condenser chamber, means providing a stream of a cooling medium flowing through said chamber, means for controlling the flow rate of said stream, means automatically operable to maintain a constant pressure in the chamber, an evaporation cup,

10 means operative to supply a continuous sample of the condensate to said cup at a constant rate, and means automatically operated in accordance with the temperature of the condensate sample in said cup to actuate said stream controlling means to effect the production of a condensate of a constant and predetermined volatility.

15 4. In apparatus for fractionating a gaseous hydrocarbon mixture by condensation to produce a condensate of constant and predetermined vapor pressure, means providing a condenser chamber, means providing a stream of a cooling medium through said chamber, flow control means for said stream, and means automatically operable in accordance with the vapor pressure of the condensate for operating said control means.

20 5. In continuously operable apparatus for fractionating a gaseous hydrocarbon mixture by condensation to produce a liquid product, an evaporation cup, means supplying a continuous sample of the said product to said cup, and means automatically operable in accordance with the temperature of the evaporating liquid in said cup for controlling said apparatus for the continuous production of said product to have a constant vapor pressure.

25 6. In continuously operable apparatus for fractionating a gaseous hydrocarbon mixture by condensation to produce a liquid product, an evaporation cup, means supplying a continuous sample of said product to said cup, and means continuously and automatically operable in accordance with the vapor pressure of said sample for controlling said apparatus for the continuous production of said product to have a constant vapor pressure.

30 7. In apparatus for fractionating a gaseous hydrocarbon mixture by condensation to produce a condensate of constant and predetermined vapor pressure, means providing a condenser chamber, means to control the condensation temperature in said chamber, and means automatically operable independently of the condensing temperature and in direct accordance with the vapor pressure of said condensate for operating said control means.

35 8. In continuously operable apparatus for fractionating a gaseous hydrocarbon mixture by condensation to produce a liquid con-

densate, means providing a condensation chamber, means to automatically maintain a constant operating pressure in said chamber, means to control the condensation temperature in said chamber, and means automatically operable in accordance with the vapor pressure of said liquid condensate for operating said temperature control means whereby said liquid condensate is of a constant and predetermined volatility.

70 9. In continuously operating apparatus for fractionating a variable hydrocarbon mixture, control means for said apparatus, means providing a liquid fraction of said mixture, and means operable in direct accordance with the vapor pressure of said liquid fraction to so effect said control means as to maintain the vapor pressure of said condensed product at a constant value.

75 10. In continuously operable apparatus for fractionating a variable hydrocarbon mixture, means providing a liquefied fraction of said mixture, an evaporation cup, means supplying a continuous sample of said fraction to said cup, and means continuously and automatically operable in direct accordance with the vapor pressure of said sample in said cup for controlling said apparatus for the continuous production of said fraction to have a constant vapor pressure.

80 11. In a continuously operating apparatus for fractionating a variable mixture of hydrocarbon vapors, a condenser receiving said mixture for condensing a fraction of the vapors thereof, and control means to variably determine the fraction of condensation in said condenser, said means operable in direct accordance with the vapor pressure of the condensed product of the condenser to continuously maintain the said vapor pressure of said condensed product at a constant value.

85 In testimony whereof, I affix my signature.
FLOYD L. KALLAM.
